SUPPORT OR CARRIAGE FOR CASH REGISTERS.

APPLICATION FILED JAN. 24, 1907.

2 SHEETS—SHEET 2.

UNITED STATES PATENT OFFICE.

CHARLES OESTERLE AND WILLIAM V. FRANK, OF SPRINGFIELD, AND WILLIAM H. ALTHOFF,
OF DAYTON, OHIO.

SUPPORT OR CARRIAGE FOR CASH-REGISTERS.

No. 872,742.

Specification of Letters Patent.

Patented Dec. 3, 1907.

Application filed January 24, 1907. Serial No. 353,929.

To all whom it may concern:

Be it known that we, CHARLES OESTERLE and WILLIAM V. FRANK, residing at Springfield, in the county of Clark and State of Ohio, and WILLIAM H. ALTHOFF, residing at Dayton, in the county of Montgomery and State of Ohio, citizens of the United States, have invented certain new and useful Improvements in Supports or Carriages for Cash-Registers and the Like, of which the following is a specification, reference being had therein to the accompanying drawings.

The present invention relates to supports or carriages for cash registers and the like.

The object of the invention is to provide a support for cash registers or other heavy devices which will be provided with a truck, the wheels of which may be moved into and out of engagement with the supporting surface, thereby rendering the support either stationary or movable; to provide an improved truck for use in connection with the support; and further to provide such a support which may be adjusted to receive a great variety of different sizes of cash registers or the like.

With these objects in view our invention consists in certain novel features of construction to be hereinafter described, and then more fully pointed out in the claims.

In the accompanying drawings, Figure 1 is a perspective view of our improved support; Fig. 2 is a longitudinal sectional view, taken on the line *x* *x* of Fig. 1 and looking in the direction of the arrows; Fig. 3 is a detail view of the frame for the truck; Fig. 4 is a longitudinal sectional view taken on the line *y* *y* of Fig. 1 and looking in the direction of the arrows; Fig. 5 is a transverse sectional view taken on the line *z* *z* of Fig. 1; and Fig. 6 is a plan view of one of the trucks, showing a slightly modified form of the same.

In these drawings we have shown our invention in its preferred form, the support being indicated as a whole by the reference numeral 1 and consisting of four side plates 2 which are preferably identical and are adjustably connected at their adjacent ends by the four corner pieces 3. The side plates are preferably of a width equal to the height of the support and of a length slightly less than the length of the corresponding side of the support and have their inner faces rabbeted along the edges thereof, as shown at 4, and are provided with longitudinally extending

slots 5, the outer edges of which are beveled, as shown at 6, to receive the head of a screw. The four corner pieces 3 are preferably identical and consist of two arms 7 of a width equal to the height of the support and each of a length sufficient to overlap the corresponding side of the support for a distance slightly less than half the length thereof. The outer faces of the arms 7 of the corner pieces are shaped to correspond to the inner faces of the side plates 2 and are provided at their upper ends with flanges or projections 8 corresponding to the rabbeted portion 4 of the side members 2, thus forming an interlocking connection between the corner pieces and the side members of the frame and permitting the outer faces of the side members 2 to lie substantially flush with the exposed outer sides of the corner pieces 3, and further permits the corner pieces and the side members to be adjusted relatively one to the other. Screws 9, extending through the slots 5 in the side members and engaging a screw-threaded aperture in the arms 7 of the corner pieces, serve to lock the side members and the corner pieces in their adjusted position.

A central connecting member or partition 26 extends transversely of the frame and is secured at its opposite ends to the side members 2 at the opposite sides thereof. This central partition is preferably constructed after the manner of the side members of the frame and has its slideable end portions secured to that portion of the side plate 2 which lies between the arms 7 of the corner pieces.

The central portion of the partition 26, which lies between the slideable ends thereof, is provided with an elongated bearing aperture for the purpose hereinafter described. The corner pieces are also preferably provided with upwardly extending brackets 10 adapted to engage the corners of the cash register, or other device which rests upon the support, and retain the same in position thereon. This construction of the base enables the same to be adjusted equally in all directions to adapt it to support any size of cash register or other device, and also permits it to be extended a greater distance in one direction than in the other to vary the shape of the base to correspond to the different registers to be supported. The arms 7 of the corner pieces 3 are provided on their inner

faces with inwardly extending flanges or projections 11 extending from the upper edge of the arm at the inner end thereof to the lower edge thereof at the outer corner of the same.

5 These projections or flanges may be formed integral with the arms 7, or may be secured thereto in any suitable manner, and are of sufficient strength to support the entire weight of the base and the device supported

10 thereon.

The adjustable wheels or truck for the support may be secured thereto in any suitable manner, that preferred being the truck shown in the drawings which consists of a

15 plate 12, which extends in a substantially horizontal plane, and is provided at its outer ends with downwardly extending portions 13 which, in turn, are provided with outwardly extending projections or flanges 14 inclined

20 to correspond to the inclined surface of the flange or projection 11 of the frame. This frame for the truck may be formed in a single piece or may be made in any suitable manner, but must be of sufficient strength to bear

25 the weight of the frame and the device supported thereon.

Suitable casters or wheels 15 are secured to the truck frame 12 in any suitable manner, but we prefer the form of caster shown

30 in the drawings and secured to the truck in the manner therein shown. In employing this form of caster we provide the plate 12 with bearing apertures 16 near the opposite ends thereof. Each aperture is screw-

35 threaded to receive the screw-threaded upper end of the bushing 17, which is provided with a central opening of slightly less diameter than the aperture 16 in the plate proper. The enlarged lower portion or flange of the

40 bushing 17 is provided with an annular groove 18 forming part of a ball race. The caster 15 is provided with a spindle having an outwardly extending flange or bearing portion 19 having formed in the upper edge

45 thereof an annular groove 20 corresponding to the groove 18 in the bushing 17 and adapted to form therewith a ball race containing the bearing balls 21. The spindle 22 of the caster extends through the bearing aperture

50 in the bushing 17 and is secured therein by a suitable screw 23, the head of which extends over the shoulder formed by the reduced portion of the bushing 17 in the aperture 16 in the plate 12. The plate 12 is provided, preferably

55 near the center thereof, with a downwardly extending lug 24 which is provided with a screw-threaded aperture extending transversely of the plate 12 and adapted to receive the screw-threaded end of the shaft 25, which is jour-

60 naled in the central plate 26 of the frame 1 and is held against longitudinal movement therein by suitable collars 27. This shaft is provided at its opposite ends with oppositely extending screw threads adapted to engage

65 the screw-threaded apertures in the frames

of the trucks at the opposite ends of the support, and, when rotated, to move these trucks toward or away from one another.

The screw-threaded portions of the rod preferably extend a considerable distance beyond the screw-threaded aperture, thereby allowing for the adjustment of the frame. The shaft 25 extends through an elongated aperture in the side plate 2 at the front of the support and is there provided with any suitable means for rotating the same in either direction, the means here shown consisting of the usual two way pawl and ratchet 28. In order that the end of the shaft with its operating means may always project beyond the side of the frame, regardless of the adjusted position of the frame, we prefer to provide the outer end of the shaft with a sliding sleeve or extension 29, which is provided with an inwardly extending pin 30, adapted to engage a groove 31 in the shaft 25, and has the operating mechanism mounted on the outer end thereof, as shown. Thus, it will be seen that the shaft will be automatically lengthened to accommodate it to the variations in the size of the support. The trucks are also made adjustable to permit the width of the support to be varied without moving the inclined members of the frame and the truck out of engagement one with the other.

95 This adjustment of the truck we prefer to accomplish in the manner shown in these drawings, which consists in dividing the plate 12 of the truck near its ends, as shown at 32, and providing the short ends thereof with inwardly extending pins 33, preferably secured thereto in a substantially horizontal plane by screwing the same in suitable screw-threaded apertures 34 in said short ends of the plate. The central portion of the plate 12 is provided with longitudinal apertures of considerable depth and adapted to register with the screw-threaded apertures of the short ends of the plate and to receive the ends of the pins 33. Set screws 35, extending through the walls of the recesses in the central portion, engage the pins 33 and retain the same in their adjusted positions.

The operation of the device will be obvious from the foregoing description. Briefly, it is as follows: The frame 1 is adjusted to receive the particular cash register, which it is to support by loosening the screws 9 and moving the corner pieces outward to the desired position, after which the screws 9 are tightened down and the frame locked in its adjusted position. With the trucks moved to the innermost position adjacent to the central partition of the frame, the wheels or casters 15 are out of engagement with the counter or other supporting surface upon which the cash register is mounted, the guides 14 are out of engagement with the guideways 11 and the lower edges of the frame rest upon the said supporting surface, thereby sup-

110 115 120 125 130

porting the register in a fixed position. When it is desired to move the register the casters 15 are caused to travel along the supporting surface by rotating the shaft 25 in the proper direction, thereby moving the trucks towards the sides of the frame and causing the inclined guides 14 of the truck to engage the lower inclined surface of the projections or guideways 11 on the sides of the frame, and, as the trucks move outward, to elevate the frame 3 and raise the same out of engagement with the supporting surface, thereby placing the entire weight of the frame, and the register supported thereby, 10 on the wheels or casters and allowing the same to be moved into any desired position, the swiveled ball bearing casters permitting the same to be readily moved in any direction. When the register has been placed in 15 the desired position, the shaft is rotated in the opposite direction and the trucks moved toward the center of the frame, thus allowing the lower edges of the frame to again come into contact with the supporting surface and 20 form a stationary support for the register.

We wish it to be understood that we do not desire to be limited to the exact details of construction shown and described, for obvious modifications will occur to a person skilled in the art.

Having thus fully described our invention, what we claim as new and desire to secure by Letters Patent, is:—

1. A device of the character described comprising a frame having a plurality of inclined surfaces, a plurality of trucks having inclined surfaces adapted to coöperate with the inclined surfaces of said frame, and means for moving said trucks in opposite directions.

2. In a device of the character described, the combination, with a frame having oppositely inclined members, of trucks having guides adapted to coöperate with the inclined members of said frame, and means for moving said trucks in opposite directions.

3. In a device of the character described, the combination, with a frame having oppositely inclined members, of trucks having inclined members adapted to coöperate with the inclined members of said frame, and means for moving said trucks simultaneously in opposite directions, substantially as described.

4. In a device of the character described, the combination, with a frame having oppositely inclined members, of trucks having inclined members adapted to coöperate with the inclined members of said frame and provided with screw-threaded apertures, and a shaft journaled in said frame and fixed against longitudinal movement, having its ends provided with oppositely extending screw threads and adapted to engage the 60 screw-threaded apertures in said trucks,

and means for rotating said shaft, substantially as described.

5. A device of the character described comprising a frame adjustable both laterally and longitudinally, wheels mounted on said frame, and means for vertically adjusting said wheels relatively to said frame.

6. A device of the character described comprising an adjustable frame having inclined guideways, and an adjustable truck 75 having guides adapted to coöperate with said guideways, and means for moving said truck relatively to said adjustable frame, substantially as described.

7. In a device of the character described, 80 the combination, with a frame comprising side members, corner pieces adjustably secured thereto, and inclined guideways carried by said frame, of trucks having guides adapted to engage said guideways, and 85 means for moving said trucks relatively to said frame, substantially as described.

8. In a device of the character described, 90 the combination, with a frame comprising side members, corner pieces having arms adjustably secured to said side members, and inclined guideways carried by said arms, of trucks having guides adapted to engage said inclined guideways, and means for moving 95 said trucks relatively to said frame, substantially as described.

9. In a device of the character described, 100 the combination, with a frame comprising side members, corner pieces having arms extending parallel to said side members and slidably connected thereto, means for locking said arms and said side members in their adjusted positions, and inclined guideways carried by said arms, of a truck, a guide carried by said truck adapted to move in said 105 guideways, and means for moving said truck relatively to said frame, substantially as described.

10. In a device of the character described, 110 the combination, with a main frame having inclined guideways, of a truck comprising a frame having downwardly extending end members, inclined flanges carried by said end members adapted to coöperate with the inclined guideways of said main frame, and 115 means for moving said truck relatively to said main frame, substantially as described.

11. In a device of the character described, 120 the combination, with an adjustable frame having inclined guideways, of a truck comprising a central member, end members adjustably secured thereto, a guide carried by said end members adapted to coöperate with the inclined guideways in said frame, and means for moving said truck relatively to 125 said frame, substantially as described.

12. In a device of the character described, 130 the combination, with an adjustable frame having inclined guideways, of a truck comprising a central portion having longitudinal

apertures in the ends thereof, end portions, pins rigidly secured to said end portions and adapted to enter the apertures in said central portion, guides carried by said end portions 5 and adapted to coöperate with the inclined guideways of said frame, and means for moving said truck relatively to said frame, substantially as described.

13. In a device of the character described, 10 the combination, with a frame having inclined guideways, and a connecting member extending transversely of said frame intermediate the ends thereof, of trucks having guides adapted to coöperate with said inclined guideways and each provided with a screw-threaded aperture, a shaft journaled in said transverse member and having its ends provided with oppositely extending screw threads adapted to engage the screw-threaded 20 apertures in said trucks, means for holding said shaft against longitudinal movement, and means for rotating said shaft, substantially as described.

14. In a device of the character described, 25 the combination, with an adjustable frame having inclined guideways, of a truck having guides adapted to coöperate with said guideways and provided with a screw-threaded aperture, a shaft mounted in said frame and 30 having a screw-threaded portion adapted to engage said screw-threaded aperture, a sleeve journaled in said frame, extending over the end of said shaft and connected thereto so as

to rotate with said shaft and to reciprocate independently thereof, and means mounted 35 on said sleeve for rotating said shaft, substantially as described.

15. In a device of the character described, an adjustable frame comprising side members consisting of vertically extending plates 40 having projections on the inner surfaces, corner pieces having arms extending parallel with said side members and provided with grooves adapted to receive said projections, and means for adjustably connecting said 45 arms to said side members.

16. A device of the character described comprising a frame having guides, a plurality of trucks having guides adapted to coöperate with the guides on said frame; the engaging 50 surfaces of one set of said guides being inclined, and means for moving said trucks in opposite directions.
